PAUL H. GRANGER, OF LOS ANGELES, CALIFORNIA

MEANS FOR PUMPING LIQUID

Application filed October 31, 1928. Serial No. 316,130.

This invention relates to improvements in means for pumping liquid and is particularly adapted and intended for pumping oil in oil wells. In the pumping of oil from deep oil wells, such as are being operated in California for example, certain difficulties have been encountered in the use of the ordinary reciprocating pumps and my invention enables oil to be pumped in such wells and obviates the difficulties referred to by employing compressed air as a pumping medium in the manner hereinafter described.

The accompanying drawings illustrate an embodiment of my invention and referring thereto:

Fig. 1 is a vertical section, partly in elevation, of the lower portion of a well provided with my improved pumping means.

Fig. 2 is a section on line 2—2 in Fig. 1.

Fig. 3 is a section on line 3—3 in Fig. 1.

Fig. 4 is a section on line 4—4 in Fig. 1.

Fig. 5 is an enlarged vertical section of a portion of the construction shown in Fig. 1.

Fig. 6 is a vertical section of the well, showing the relation of the parts shown in Figs. 1 and 5 to the general well construction.

Referring to the drawings, a well casing is indicated at 1, said casing extending from the ground level to the oil or liquid stratum

or oil sand from which pumping is to be effected, the casing being provided in the usual manner with a perforated section for admitting oil from such oil sand to the interior of the casing. Within the casing is provided a vertical liquid delivery pipe or oil line 2 extending from the ground level to a suitable point below or in the vicinity of the level at which the oil or liquid stands in the casing and alongside of this pipe 2 is provided a vertical pumping cylinder or chamber 3 located near the lower end of the pipe 2 in position to be submerged in the oil or liquid within the casing, said cylinder or chamber 3 being of sufficient height and diameter to provide the necessary pumping capacity. Chamber 3

communicates through a passage 7 and an upwardly opening check valve 4 with the liquid delivery pipe 2.

An air or gas pressure line 5 extends from the ground level to the pumping chamber

cylinder 3 and communicates with said pumping cylinder through a valve controlled port as hereinafter described, said pipe 5 being connected at its upper end to any suitable means, such as a compressor indicated at 6 in Fig. 6 for supplying compressed air or gas thereto. Suitable valve means are provided for controlling admission of compressed air from the pipe 5 to cylinder 3 and exhaust of air or gas from said cylinder. Said valve means may comprise a valve sleeve 8 mounted to slide in the cylinder 3 and provided, if necessary, with suitable packing means or other means to insure a gas tight joint between the valve and the wall of the cylinder 3, said valve slide being provided with a port 10 adapted to communicate in different positions of the valve sleeve with the port 11 for the compressed air pipe 5 with an air exhaust port 12. Chamber 3 is also provided with an inwardly opening check valve 13 at its bottom, for admission of oil or liquid to be pumped.

The valve sleeve 8 may be operated by a valve rod or stem 15 extending through a packing box or gland 16 in the top of the cylinder 3 and provided at its upper end with a piston 17 working in a cylinder 18 which is provided with means for intermittently admitting operating fluid, such as compressed air, above and below the piston 17 to reciprocate said piston and the valve stem and valve connected thereto. For this purpose a slide valve 20 may be provided within a valve chest 21 and controlling communication between the respective end portions of the cylinder 18 and inlet and exhaust passages 22 and 23 in the manner of a reciprocating steam engine, said slide valve being operated by a valve stem 26 connected thereto and provided with tappets 28 and 29 operated by an arm 30 on the main valve rod 15 aforesaid, in such manner as to control the operation of the valve in the manner hereinafter set forth and to thereby cause intermittent vertical reciprocation of the main valve 8 so as to put the cylinder 3 in communication with the compressed air line 5 or with the exhaust opening 12.

As the pressure required to operate the main valve 8 will generally be considerably less than the pressure required for lifting the column of oil in the stand pipe 2, I prefer to provide a reducing valve 38 of any suitable type, which is inserted in a pipe line 34 communicating with the compressed air line 5 and with the valve chest 21 so as to supply to the said valve chest air at a pressure which may be only a small fraction of the pressure in the compressed air pipe 5.

I prefer to provide means whereby compressed air is admitted directly to the oil line or pipe 2 during the intervals of time when the compressed air is shut off from the cylinder 8. For this purpose a valve may be provided comprising a movable valve member 36 sliding in a valve chamber 37 communicating through pipe 38 with the compressed air pipe 5 and through a pipe connection 39 opening into valve chamber 37, with the oil pipe or line 2, the opening of pipe 39 into chamber 37 being so positioned as to be closed by valve member 36 only when the latter is in raised position, the valve member 36 being connected by stem 40 to the valve 20 aforesaid, so as to operate in synchronism therewith as hereinafter described.

A distributing nozzle 35 is preferably provided at the outlet of pipe 39 to cause the air or gas to be distributed in the form of fine bubbles throughout the column of liquid in pipe 2, and a baffle plate 41 may be mounted in pipe 2, to ensure that all of the liquid passing in said pipe is brought into effective contact with the gas ensuing from nozzle 35.

In order to properly regulate the motion of the main valve 8 by the operation of the piston 17 I prefer to provide means for retarding the motion of said valve so as to give any desired period of operation for same. For this purpose a cylinder 42 may be provided, in which operates a piston 43 connected by stem 44 to the piston 17. The cylinder 42 is provided with ports or passages 45 and 46 at opposite ends thereof and communicating with one another through a valve 47 which operates to constrict or control communication of fluid between opposite ends of the cylinder 42, so as to resist the movement of piston 43 therein. In order to produce the most effective control I prefer to fill the cylinder 42 and the passages communicating therewith with a liquid, such as oil. The resistance to flow of the liquid afforded by reason of the constriction of valves 47 serves to retard the motion of the piston 43 to any desired extent and thereby control the period of operation of the main valve 8.

It is desirable in some cases to provide automatic control of the operation of the pumping means in correspondence with the amount of oil supply in the well and for this purpose I may provide the valve 47 with an arm 47' connected to a piston 48 working in a cylinder 49

in such manner that the pressure of the column of oil in casing 1 above the cylinder tends to force the piston down against the operation of a spring 48' and to thereby tend to open the valve 47 in correspondence to the height at which the oil stands in the casing 1 and to effect more rapid operation of the valve 8 when the oil level is high and the slower operation of the valve 8 when the oil level is low. The effect of this method of control is to cause the pumping operation to proceed more rapidly when there is more oil to be pumped and less rapidly when the oil supply falls off.

In pumping oil or other liquid from deep wells it is necessary to apply air or gas at high pressure to the pumping cylinder 3 and to continue such application during the expulsion of the oil or liquid from said cylinder during each pumping operation. It follows that when the valve 8 is moved to exhaust position the air will escape from said cylinder at high pressure and in order to utilize such high pressure air as fully as possible, I prefer to provide an exhaust pipe 50 leading from exhaust outlet 12 upwardly within the casing 1 to a suitable point in the oil standpipe 2, for example about half way up the well as shown in Fig. 6, so that the exhaust air from the pumping cylinder will be delivered into the column of oil into the standpipe 2 and assist in raising the oil by air lift action.

I prefer to provide the liquid delivery pipe 2 with universal joints 52 to permit the pipe to pass bends in the well.

The operation is as follows: In the position of the parts shown in Fig. 5, the main valve member 8 is in lowered position, shutting off communication between the compressed gas line 5 and pumping chamber 3, and opening communication between the pumping chamber and exhaust pipe 50, so that the gas in said chamber will escape through the exhaust pipe, and will be distributed into the liquid delivery pipe 2. Oil or liquid will then enter the pumping chamber through the opening controlled by check valve 13, which opens inwardly with respect to the pumping chamber. These operations take place while the main valve member 8 is approaching and leaving its lowermost position, it being understood that as said valve member approaches such position, the slide valve 20 is moved by operation of arm 30, so as to reverse the connections from the pressure pipe 5 and exhaust passage 23 to opposite ends of cylinder 18, so as to cause the main valve member 8 to begin to move upwardly. In the upward movement of valve member 8, exhaust port 12 is first closed and eventually port 11, communicating with the compressed gas pipe 5, is opened, whereupon gas under pressure will enter chamber 3 from pipe 5, forcing the liquid in chamber 3 through check valve 4 (which opens outwardly with respect to the pumping

chamber) into the liquid delivery pipe 2. On reaching the upper limit of its stroke the arm 30 on the stem of main valve member 8 operates slide-valve 20 to again reverse the movement of said main valve member so as to restore the parts to the starting position above referred to.

By operation of valve means 47, restricting the flow of liquid between opposite ends 10 of cylinder 42, the movement of the main valve member is retarded sufficiently to permit the operations above mentioned to be performed effectively.

During the time that compressed gas is 15 shut off from the pumping chamber, valve 36 is opened by operation of stem 40 to admit such gas to the liquid delivery line, so as to distribute air or other gas into the column 20 of liquid and correspondingly diminish the weight of the column and the amount of power required to be applied to the pumping chamber.

I claim:

1. An apparatus for pumping liquids from wells comprising a liquid delivery pipe and a compressed gas supply pipe both extending within the well from the top of the well to the vicinity of the liquid to be pumped, a pumping chamber within the well in position 25 to be submerged by the liquid to be pumped and communicating with the liquid delivery pipe and provided with a gas inlet port communicating with the compressed gas supply pipe, and with an exhaust port, a check valve 30 opening outwardly with respect to the pumping chamber and controlling communication between the pumping chamber and the liquid delivery pipe, a check valve opening inwardly with respect to the pumping chamber and 35 controlling entry of liquid from the well to the chamber, said pumping chamber being formed as a vertical chamber, a main valve member movable vertically in said cylinder and cooperating with the said ports of the 40 pumping chamber, fluid pressure operated means located within the well for operating said valve member to alternately open and close said ports, control valve means located within the well and operated by the movement of said main valve member to control 45 the operation of said fluid pressure operated means, means for supplying operating fluid under the control of said control valve means to the said fluid pressure operated means, and 50 means for supplying compressed gas to the compressed gas supply pipe to force liquid from the pumping chamber into the liquid delivery pipe when the communication between the compressed gas supply pipe and 55 the pumping chamber is opened by operation 60 of said main valve.

2. An apparatus as set forth in claim 1 and comprising, in addition, fluid pressure operated means for retarding the movement 65 of said main valve member and means re-

sponsive to the pressure of the liquid in the well adjacent the pumping chamber for regulating the amount of retardation by said fluid pressure operated means.

3. An apparatus as set forth in claim 1 and comprising in addition, a valve operated in synchronism with the operating means of said main valve member to open communication between the compressed gas supply pipe and the liquid delivery pipe alternately with the intervals of communication between the compressed air pipe and the pumping chamber, so as to distribute gas into the column of liquid in said delivery pipe.

4. An apparatus as set forth in claim 1 and comprising in addition, fluid pressure operated means responsive to the pressure of the liquid in the well adjacent the pumping chamber and controlling the operation of the main valve member so as to effect more rapid operation of said valve member when the level of the liquid in the well is high, and slower operation of said valve member when the level of the liquid in the well is low.

In testimony whereof I have hereunto subscribed my name this 22nd day of October, 1928.
